UNITED STATES PATENT OFFICE.

WILLIAM H. ATKINS, OF MEDFORD, MASSACHUSETTS, ASSIGNOR TO JOSEPH B. McCALL, OF PHILADELPHIA, PENNSYLVANIA, PRESIDENT OF ASSOCIATION OF EDISON ILLUMINATING COMPANIES, IN TRUST FOR SAID ASSOCIATION.

DESIGN FOR A BADGE.

SPECIFICATION forming part of Design No. 37,404, dated April 18, 1905.

Application filed March 13, 1905. Serial No. 249,960. Term of patent 14 years.

To all whom it may concern:

Be it known that I, WILLIAM H. ATKINS, a citizen of the United States, residing at Medford, in the county of Middlesex, State of Massachusetts, have invented a new, original, and ornamental Design for a Badge, of which the following is a specification, reference being had to the accompanying drawing, forming part thereof.

The figure is a face view of a badge, showing my invention.

I claim—

The ornamental design for a badge as shown.

WILLIAM H. ATKINS.
